UNITED STATES PATENT OFFICE.

CLIFFORD SPRAGUE, OF ST. LOUIS, MISSOURI.

HACKSAW-FRAME.

1,190,477.

Specification of Letters Patent.

Patented July 11, 1916.

Application filed March 17, 1916. Serial No. 84,921.

To all whom it may concern:

Be it known that I, CLIFFORD SPRAGUE, a citizen of the United States, residing at St. Louis, State of Missouri, have invented new and useful Improvements in Hacksaw-Frames, of which the following is a specification.

This invention relates to improvements in hack saw frames and has particular application to an adjustable frame.

In carrying out the present invention, it is my purpose to provide a hack saw frame which may be shortened and lengthened to fit saw blades of different lengths and wherein the saw blades may be adjusted toward and away from the outer ends of the legs of the frame so as to facilitate the use of the saw.

It is also my purpose to provide a hack saw frame wherein the saw blade may be readily and conveniently applied to the frame and detached therefrom and wherein the component parts of the frame will be so arranged and correlated as to reduce the possibility of derangement to a minimum.

With the above and other objects in view, the invention consists in the construction, combination and arrangement of parts hereinafter set forth in and falling within the scope of the claims.

In the accompanying drawing; Figure 1 is a view in side elevation, partly in section, of a hack saw frame constructed in accordance with my present invention, the saw blade being shown in position. Figs. 2, 3, 4 and 5 are views of details of the invention.

Referring now to the drawing in detail, 1 designates a substantially U-shaped hack saw frame embodying a central member 2 and legs 3, 3 arranged at right angles to the central member and spaced apart in parallelism. The central member 2 of the frame is formed of two longitudinally adjustable overlapping sections 4 and 5 and, in the present instance, the overlapping end of the section 5 is formed with an outwardly projecting lug 6 carrying a pin 7 normally engaging the inner edge of the section 4, while formed in the inner edge of the section 5 and spaced apart suitable distances are notches 8 adapted to engage a pin 9 carried by the overlapping end of the section 4. By means of this construction, it will be seen that the sections 4 and 5 may be swung relatively to each other to disengage the particular notch 8 from the pin 9 and the sec-

tions adjusted to vary the length of the frame and when the frame has been adjusted to the desired length the section 5 is swung to engage the particular notch 8 with the pin 9, the pins 9 and 7 coöperating to hold the sections in adjusted position.

In accordance with my present invention, the outer edge of one leg 3 is formed with notches 10 spaced apart longitudinally of such leg, while the other leg 3 is bifurcated for the major portion of its length as at 11 and formed in the outer edges of the limbs of the bifurcated portion are notches 12 spaced apart longitudinally of the leg. 70 Mounted upon each leg 3 is a collar 13 capable of sliding movement along the leg and formed on the inner surfaces of the collars 13 contiguous to the outer edges of the legs are teeth 14 adapted to engage the notches 75 in the legs to hold the collars in adjusted position on the respective legs. Interposed between the inner surfaces of the collars 13 and the inner edges of the respective legs are leaf springs 15 that act to hold the teeth on 80 the collars in engagement with the corresponding notches so that accidental longitudinal movement of the collars along the legs will be prevented.

Passed through the collar 13 on the bifurcated leg and between the limbs of such bifurcated leg is a screw shank 16 and threaded onto the outer end portion of the shank is a nut 17 and also threaded upon the outer end portion of the shank beyond the 90 nut 17 is a handle 18. The inner end portion of the shank 18 is preferably divided into longitudinal stationary and movable sections 19 and 20 respectively placed in face to face contact and formed on the flat 95 face of the stationary section is a pin 21, while formed in the movable section is an opening 22 adapted to receive the pin 21. Threaded onto the shank and surrounding the sections 19 and 20 is a securing collar 23 acting to hold the sections in shank formation and adapted to release such sections so that the movable section may be removed from the stationary section when it is desired to detach the saw 100 blade from the frame. Formed on the inner side of the collar 13 on the leg 3 remote from the shank 16 is an inwardly projecting block 24 undercut at its inner end as at 110 25 and provided with a flat surface 26 contiguous to the undercut. The flat surface 26 is provided with a pin 27 that coöperates

with the pin 21 to hold the saw blade in the frame.

In practice, the sections of the U-shaped frame 1 are adjusted longitudinally to the desired length and one end of the saw blade hooked over the pin 27 on the block 24 and the other end of the saw blade hooked over the pin 21 and clamped between the sections 19 and 20 of the shank. The collars 13 may 10 be moved along the legs 3 so that the saw blade may be moved toward or away from the central member of the frame and when the collars are in the desired positions the teeth 14 engage the adjacent notches 10 to 15 hold the saw blade against accidental movement.

While I have herein shown and described the preferred form of my invention by way of illustration, I wish it to be understood 20 that I do not limit or confine myself to the precise details of construction herein described and delineated, as modification and variation may be made within the scope of the claims and without departing from the 25 spirit of the invention.

I claim:

1. A hack saw frame of substantially

U-form having one of the legs thereof bifurcated, collars carried by said legs and adjustable longitudinally thereon, a securing shank passed through one of said collars and between the limbs of said bifurcated leg, and blade holding means carried by said shank and the remote collar respectively.

2. A hack saw frame of substantially U-form having one of the legs thereof bifurcated, collars carried by said legs and adjustable longitudinally thereon, a securing shank passed through one of said collars and between the limbs of said bifurcated leg, a nut threaded on said shank and bearing against said collar whereby the shank may be moved longitudinally to tension the blade, and blade holding means carried by said shank and the remote collar respectively.

In testimony whereof I affix my signature in presence of two witnesses.

CLIFFORD SPRAGUE.
